FID

Venancio Adriás, II, Chevy Chase, Md., assignor
of one-half to Otis Lee Williams, Jr., Washington, D. C.

Application March 26, 1942, Serial No. 436,349

1 Claim. (Cl. 57—23)

This invention consists of a hand fid having for an object to greatly expedite rope splicing operation, at the same time facilitating training or threading of the fid and its strand through the rope body in a single continuous operation.

It is also within the contemplation of this invention to provide a hand fid especially adapted for rapid and positive repair operations, as required on board ship, since the splice carrying fid is completely movable through the rope without interruption or the necessity of retracting the fid once the operation has been initiated.

The fid is of simple inexpensive construction capable of effective use even by a person unskilled in the art, the threading strand being positively held from displacement while urged between juxtaposed strands of the rope, disengagement of the fid from its strand being automatically effected as soon as the fid clears the said juxtaposed strands.

Other objects of the invention will be manifest from the following description of the present preferred form of the invention, taken in connection with the accompanying drawing, wherein:

Fig. 1 is a perspective view of a hand fid constructed in accordance with the present invention, illustrating its application;

Fig. 2 is a top plan view of the fid, per se;

Fig. 3 is a longitudinal sectional view of the fid taken on the line 3—3 of Fig. 2 showing a fragment of a rope strand in the fid recess;

Fig. 4 is a top plan view of the fid with its lid removed; and

Fig. 5 is a cross sectional view of the fid taken on the line 5—5 of Fig. 3 showing a strand of rope mounted therein.

The device of the present invention consists of a body 5 which may be made of wood or other suitable material. The body is of generally cylindrical configuration, one end 6 thereof being pointed. The opposite end is provided with an axial recess 7 extending from the butt terminal of the body to a point approximately midway the ends of the latter. The recess is of sufficient depth to accommodate a strand 8 of rope. In order to prevent displacement of the strand, I employ a suitable cover or lid 9 for the recess which serves as a clamp to urge the strand 8 against

the wall of the recess 7 before and during the threading operation of the strand. The cover 9 may be made of metal or other suitable material, the inner end thereof being hinged, as indicated at 10, permitting the free end of the lid to be swung away from the body preparatory to inserting the strand 8 in the recess 7. The inner wall of the recess 7 is dipped to provide a finger engaging depression 11 to facilitate sliding axial movement of the body, as well as lateral rocking movement while forcing the fid through the rope.

In use of this invention, a strand 8 which is adapted to be threaded through adjacent strands of a rope, is deposited in the recess 7, and the lid 9 closed thereover in an obvious manner. The pointed end 6 of the fid body is then urged between adjacent strands 12 of a rope. The fingers of the operator are held in engagement with the lid 9 until the latter reaches the zone of the strands 12. The thumb or thumbs (depending on the amount of pressure to be applied) of the operator, is or are engaged with the butt end of the body to urge the latter through the strands 12. As soon as the butt end of the body has cleared the rope strands, pressure on the lid 9, is released, correspondingly releasing the threading strand 8. Of course, at the completion of this cycle of operation, the threading strand 8 has been drawn through the adjacent strands 12 of the rope sufficiently for the free end of the threading strand to be grasped by the operator and urged through the rope strands to any desired point.

Although I have herein shown and described a preferred embodiment of this invention, it is of course to be understood that various changes may be made therein, within the scope of the claim hereto appended.

What is claimed is:

40 A hand fid for rope splicing including a body, one end of which is pointed to facilitate its engagement between adjacent rope strands, the opposite end of the fid being recessed to receive a strand to be threaded, the inner terminal wall of the recess having a finger depression to permit application of stress at the axial line of the fid while feeding the latter between the strands.

VENANCIO ADRIAS, II.
